SLUG RECEIVER

Paoli G. Woodliff, Houston, Tex., assignor to
 Mohr Lino-Saw Company, Chicago, Ill., a corporation of Illinois

Application April 1, 1947, Serial No. 738,507

5 Claims. (Cl. 199—61)

1

The present invention relates to an improved form of slug guide for slug-sawing apparatus, such as are used in connection with type casting machines, such slug-sawing apparatus serving to saw into different lengths the type slugs cast by those machines. One such slug-sawing apparatus or attachment widely known in the trade is the "Mohr Lino-Saw," and my invention has particular application to that device. This Mohr Lino-Saw is widely sold as an attachment unit for mounting upon type casting machines typically represented by the well known "Linotype" or "Intertype" machines.

In many instances it is desirable to have the type slugs of different lengths so as to enable the type to be assembled more readily around advertising cuts, illustrations, etc. As above stated, the type casting machine is frequently provided with a slug-sawing attachment, such as the aforementioned Mohr Lino-Saw, for this very purpose of cutting the slugs to different lengths, although the different lengths can also be obtained by making appropriate adjustments in the type casting machine. When the slugs are of different lengths a problem is introduced in guiding the slugs into proper position down upon the assembly platform. The improved slug guide of my invention has particular reference to the guiding of these varied length type slugs down to the assembly platform where they are assembled in galley form or upon a galley stick. As each slug slides down the delivery chute leading to this assembly platform it comes to rest on the platform alongside a pusher member or slug jogger. This jogger or pusher then operates automatically in a lateral or horizontal direction to push the slug sidewise into its assembled relation to the preceding slugs of the galley. Each slug should be guided down to the bottom of the chute or to the bottom edge of the platform, and the lateral support or guidance of the slug should be maintained until the slug jogger moves the slug laterally into its assembled position in the galley. When producing slugs of different lengths, the slug guide should guide the short slugs as well as the long slugs all of the way down to the terminal position at the bottom of the chute, or bottom edge of the assembly platform, but the guide should not interfere with the horizontal movement of the jogger. Heretofore, this has entailed the use of a folding type of guide made up of folding pivoted sections, such as is disclosed in Patent No. 1,358,972 issued to Charles L. Mohr on November 16, 1920. The pivoted sections of this folding guide are adapted to be fold-

2

ed downwardly or upwardly to increase or decrease the effective length of the guide so as to accommodate short or long slugs respectively. However, this folding of the guide sections downwardly or upwardly entails a manual operation to be performed by the type casting operator each time that a change is made from a long slug to a short slug or vice versa. This places another duty upon the type casting operator, and if he forgets to perform the guide folding or unfolding operation there is the likelihood of jamming or improper assembly of the slugs upon the assembling platform.

The fundamental object of the present invention is to avoid these difficulties by providing an automatically operating guide which automatically moves into and out of guiding position in timed sequence with the operation of the slug jogger. This automatically operating guide is effective to guide short slugs, long slugs and slugs of any intermediate length down to the terminal position at the lower edge of the assembly platform. At the same time, this automatically operating guide cannot interfere with the function or motion of the slug jogger because the guide is automatically moved up out of guiding position when the jogger pushes the slug laterally over into assembled position on the platform or galley. Thus, the type casting operator is relieved of the duty of making any changes or adjustments in the guide mechanism when changing from long slugs to short slugs or vice versa.

Other objects, features and advantages of the invention will appear from the following detailed description of one preferred embodiment thereof. In the accompanying drawings illustrating such embodiment:

Figure 1 is a front perspective view showing my improved guide mounted on a slug-sawing attachment for type casting machines;

Figure 2 is a fragmentary plan view showing the relation of the automatically moving guide to the assembling platform and slug jogger; and

Figure 3 is a transverse sectional view taken approximately on the plane of the line 3—3 of Figure 2.

My invention has its principal utility when mounted on a slug-sawing attachment for type casting machines, and that is the relation in which I have illustrated it in Figure 1. As well known to those skilled in the art, this figure shows a "Mohr Lino-Saw," such being a slug-sawing attachment for type casting machines. Slug-sawing attachments of this general type are disclosed in prior Patent No. 1,264,541 issued to

Charles L. Mohr on April 30, 1918, and in the aforementioned Patent No. 1,358,972 issued to Charles L. Mohr on November 16, 1920.

In Figure 1 the vertical saw shaft 10 is the shaft that carries the rotary disk type of saw 11 that cuts the type slugs. The front and side portions of the circular saw are enclosed within a housing 12 which is capable of sliding up and down along guide rails carried by the main bracket of the slug-sawing attachment. This housing carries the shaft 10 and saw 11 with it for cutting the slugs at different heights. Behind this assembly of slug-sawing parts is the conventional mold wheel of the type casting machine provided with mold slots in which type slugs are cast, usually about 5" in length. As is well known to those skilled in the art, associated with the mold wheel is a reciprocating slug ejector which is adapted to force the type slug out of the mold. As the slug is pushed out of the mold by the ejector it passes through a conventional trimming mechanism by which it is sized as to thickness. In front of this trimming mechanism is disposed the slug cutting saw 11 within its housing 12. The saw is operative to cut each slug into an upper and a lower part, the point of cutting and the length of each part being dependent upon the vertical adjustment of the saw blade. The upper part of the slug is waste and passes out of the machine down a waste chute, not shown, while the lower part of the slug carries the printing characters and is the finished type slug which it is desired to produce from the type casting machine. This lower or printing portion of the slug is designated S in its entirety, this lower portion dropping vertically down a narrow vertical guide chute 20 as soon as it is severed from the upper part of the original slug. From the vertical chute 20 the slug is deflected by curved guide plate 21 in a diagonally downward and forward direction into a delivery chute 22 which extends across the top surface of a downwardly and forwardly sloping assembly platform 23. This assembly platform has a lower marginal flange 24 which constitutes an end stop defining the terminal or delivered position of the slug in its travel down the delivery chute 22 into the final position preparatory to being moved laterally by the slug jogger. It will be observed from Figure 2 that the platform 23 is wide enough from its lower marginal flange 24 to its upper edge 25 to receive the longest slugs, and all of the slugs, of whatever length, slide down said platform to this terminal position in the delivery chute 22 with their lower ends resting against the flange or rib 24 at the bottom edge of the platform. At this terminal position the right hand side of the delivery chute 22 is defined by the slug jogger 27 and the left hand side of the delivery chute is defined by the automatically operating guide arm 28 to which I have previously referred. At a predetermined time in the cycle, after a slug S has been delivered into the bottom of the delivery chute 22, the slug jogger 27 is automatically caused to move laterally toward the left for shifting this slug over into its proper assembled position in the galley on the assembling platform 23. Concurrently, with this lateral shifting movement of the slug jogger, the guide arm 28 is automatically caused to swing upwardly to a position which will clear the slug so as to enable the slug to be shifted over into this position of assembly in the galley. Concurrently, with the return movement of the

jogger back to its right hand position, the guide arm 28 is swung down into its original guiding position, whereby the parts are placed in readiness to receive the next type slug S delivered down into the delivery chute 22.

The slug jogger 27 preferably consists of a long narrow plate having its upper end portion inclined gradually toward the right and having a laterally bent upward tip 27', whereby to gradually deflect the descending slugs into the narrower delivery space at the bottom end of the delivery chute. This jogger plate is suitably secured to a right angle casting 31, in the vertical flange of which are riveted two spaced guide pins 32. These guide pins have guided slidable support in guide bosses 33 formed integrally with a mounting casting 34 which is fixedly secured to the machine below the assembly platform 23. Coiled compression springs 36 are assembled over the guide pins 32 and extend into counterbores in the guide bosses 33, these springs normally tending to shift the jogger plate 27 toward the right into either one of two normal positions. These two positions are selectively predetermined by the rotation of a knurled stop head 38 (Figures 1 and 3). This stop head is mounted for a half rotation in any suitable manner, such as by a pin extending therefrom inwardly into a stationary mounting sleeve 39 and having a stud or pin projecting therefrom for rotative movement in an arcuate slot in the mounting sleeve. When the stop head is revolved to one position its inner end surface forms a stop for limiting the shifting movement of the jogger to the right; and when the stop head is rotated through a half revolution a notched recess 38b in the head is brought into position where it functions as the end stop for the movement of the jogger. In this latter situation, the jogger can move slightly further to the right for accommodating other widths or thicknesses of type slugs. This is conventional practice in the Mohr Lino-Saw.

Referring now to the actuating mechanism which automatically shifts the jogger toward the left at a predetermined time after a type slug has been delivered down into the delivery chute 22, this actuating mechanism comprises an actuating lever 41 pivotally mounted intermediate its ends on the downwardly extending pivot pin 42. The pivot pin 42 is carried by a mounting bracket 43 which is secured by screws or bolts 44 to the main supporting casting 34. When the lower arm of the lever 41 swings in a clockwise direction toward the left, it transmits shifting movement to the slug jogger through a compression spring 46. This spring is loosely confined between the actuating lever and the jogger by a guide pin 47 which passes loosely through an aperture in the end of the lever and through the spring and into the jogger casting 31. The purpose of this spring is merely to permit the motion of the jogger to be interrupted without injury to the type slugs if there should be any jamming or interference of the slugs. As best shown in Figure 2, the upper arm of the actuating lever 41 extends into the bifurcated lower end 51a of a bell crank lever 51. A pivot pin 52 extending through this bifurcated end engages in an elongated opening 53 in the actuating lever 41, for transmitting motion from the bell crank lever to the actuating lever. The bell crank lever is pivotally mounted on a pivot stud 54 extending downwardly from the mounting bracket 43. The other arm 51b of the bell crank

lever extends into an actuating yoke or clevis 56, these two parts being pivotally connected by a pivot screw 57 extending through the clevis and through a pivot opening in the lever arm. Extending rearwardly from the yoke or clevis 56 is a thrust pin 58 which has guided support in a guide boss 59 formed at the upper or inner end of the mounting bracket 43. The type casting machine comprises automatic actuating mechanism which is operative to impart outward thrusting movement to the thrust pin 58, such outward thrusting movement operating through the bell crank lever 51 and actuating lever 41 to cause lateral shifting movement of the slug jogger 27 to the left for shifting the previously delivered slug over into its proper assembled position in the galley. This automatic actuation of the slug jogger is a conventional practice well known to those skilled in the art, and occurs when the ejecting plate is forced back against the vise frame of the type casting machine to receive the succeeding slug.

Referring now to the automatically operating slug guide 28, this is preferably in the form of a long narrow plate which may be punched from sheet metal or formed as a casting. The upper end of this guide plate has a pivot hole 28a for receiving a pivot screw 61, and an intermediate portion of the guide plate is formed with an arcuate slot 28b which has free swinging movement over a limiting screw 62. The pivot screw 61 and limiting screw 62 thread into tapped holes in a stationary upwardly extending guide plate 63. A mounting flange 64 projects laterally from the bottom edge of the guide plate 63, and is apertured or notched for receiving fastening screws 65 by which the plate 63 is fixedly attached to adjacent stationary parts of the slug-sawing machine, although it could be attached to the assembly platform 23. The upper outer corner of the guide plate 63 is inclined outwardly to form a deflecting guide surface 67 for deflecting any tipped slugs into proper position within the delivery chute. That portion of the plate 28 which projects beyond the lower end of the guide plate 63 has its lower edge notched out to form a long sloping bottom edge 28c. It is this notched end portion that constitutes the movable guide adapted to engage the adjacent side surfaces of the type slugs, and the purpose of the sloping bottom edge 28c is to reduce the range of swinging movement that the guide plate is required to go through in order to clear the top edge of the type slug. That is to say, by forming this bottom edge 28c along a slope, as indicated, this bottom edge is substantially parallel with the outer or top edge of the slug the instant that the slug is cleared, so that the entire length of the slug can be cleared by a smaller range of movement of the guide.

Automatic operating motion is transmitted to the movable guide arm 28 through the instrumentality of an operating arm 71. The upper end of this arm is formed with a longitudinal slot 72 through which pass two cap screws 73 which tap into holes 28d in the guide arm. This attachment of the operating arm to the guide arm 28 permits the operating arm to be adjusted upwardly or downwardly relatively to the guide arm. The operating arm 71 extends downwardly above the top edge of the platform, the arm preferably being curved substantially concentrically with respect to the pivotal motion around pivot screw 61. The lower end of the operating arm is provided with a laterally bent extension

75 which lies substantially in the path of forward movement of the front end of actuating yoke 56. The forward motion of this yoke when transmitting actuating motion to the slug jogger 5 27 also transmits motion to the end 75 of the operating arm 71 for swinging the movable guide 28 upwardly to a raised position where it clears the top or forward edge of the type slug. If desired, some lost motion space may be provided 10 between the bent end 75 of the operating arm and the yoke 56, so that the slug jogger will have actually started in its movement to the right for moving the type slug laterally before the slug guide 28 is started in its upward motion. These 15 parts can be accurately timed so that the guiding function of the slug guide 28 is maintained right up to the point where the slug jogger is actually shifting the slug, and possibly pressing it lightly against the side of the guide 28. The provision of the compression spring 46 for transmitting resilient pressure to the slug jogger insures that the slug guide 28 can be moved to its clearing position, even if the type slug should be pressed up against the side of this guide 20 arm. With the guide arm raised to its slug clearing condition, the slug is moved over into its assembled position at the right hand end of the galley. Thereupon, the slug jogger starts to move back through its return stroke toward the 25 right, and substantially concurrently therewith the slug guide arm 28 starts swinging down to its normal position. These two parts are automatically returned to their normal positions in time phase with the automatic cycle of the type 30 casting machine so that these parts have been restored to their normal positions before the next type slug is delivered down into the delivery 35 chute 22. It will thus be seen that the automatically movable guide arm 28 is always effective to exert its guiding function on the type 40 slug irrespective of whether the latter is a long slug, short slug or slug of any intermediate length, and that this guide is automatically moved upwardly to a position where the slug is 45 cleared when the slug jogger starts moving the slug laterally, all without requiring any attention on the part of the type casting operator and without requiring any adjustment or change 50 of parts when delivering long slugs, short slugs or slugs of any intermediate length.

While I have illustrated and described what I regard to be the preferred embodiment of my invention, nevertheless it will be understood that such is merely exemplary and that numerous 55 modifications and rearrangements may be made therein without departing from the essence of the invention.

I claim:

1. In slug-sawing apparatus for use in connection with a type casting machine wherein 60 said apparatus embodies means for sawing type slugs produced by said typesetting machine, the combination therewith of an inclined platform serving as a galley for the type slugs, a delivery chute for directing the slugs from said sawing means down upon said platform, a slug jogger at one side of said delivery chute operable to push the type slug laterally on said platform, an automatically moving guide at the other side of 65 said delivery chute, means pivotally supporting said guide for vertical movement in an upward direction away from said platform to clear each slug as it is pushed laterally by said jogger, an operating lever arranged to transmit operating 70 motion to said slug jogger, a bell crank lever 75

operatively connected to transmit motion to said operating lever, actuating linkage responsive to the cyclical operation of said type setting machine for actuating said bell crank lever, an arm extending from said automatically moving guide and disposed in the path of said actuating linkage whereby said guide is caused to swing upwardly to its slug clearing position in automatically timed relation to every actuation of said jogger, and a cushioning spring interposed between said operating lever and said slug jogger whereby the motion of said jogger can be yieldingly interrupted if the jogger should press a slug laterally against said automatically moving guide before said guide is raised to slug clearing position.

2. In an automatic slug guide for use on slug-sawing attachments to type casting machines wherein the slug-sawing attachment has a slug delivery chute leading to a galley platform and has a slug jogger for pushing the sawed and unsawed slugs laterally from said chute into galley position on said platform, the combination for use therewith of a mounting bracket adapted for mounting on said attachment, a slug guide pivotally supported at its upper end on said mounting bracket and adapted to extend down along one side of said chute substantially parallel with said slug jogger, an arcuate motion limiting slot in said guide, a stop member carried by said mounting bracket and engaging in said slot for limiting the motion of said guide, an operating arm adapted to extend from said guide down through said platform and into position to be actuated by the mechanism which actuates said jogger each time that the jogger is actuated, whereby said guide is swung upwardly to slug clearing position in predetermined timed relation to every operation of said jogger, and means adjustably securing said operating arm to said guide enabling the position of said operating arm to be adjusted relatively to said guide, the upwardly swinging end portion of said slug guide having its lower edge notched out to form a sloping bottom edge which lies substantially parallel to said platform and to the top edge of the slug in its slug clearing position.

3. In slug-sawing apparatus for use in connection with a type casting machine wherein said apparatus embodies means for sawing type slugs produced by said typesetting machine, the combination therewith of an inclined platform serving as a galley for the type slugs, a delivery chute for directing the slugs from said sawing means down upon said platform, a slug jogger at one side of said delivery chute having a thrusting face operable to push the type slug laterally on said platform, an automatically moving guide at the other side of said delivery chute, pivot means for said automatically moving guide defining a pivot axis therefor disposed above said platform and extending substantially at right angles to said delivery chute, slug and thrusting face of said jogger, whereby said automatically moving guide is capable of being swung upwardly in a vertical plane remaining parallel to the adjacent side surface of the type slug so as to clear each slug as it is pushed laterally by said jogger, an operating lever arranged to transmit operating motion to said slug jogger, a bell crank lever operatively connected to transmit motion to said operating lever, actuating linkage responsive to the cyclical operation of said typesetting machine for

5 10 15

actuating said bell crank lever, an arm extending from said automatically moving guide and disposed in the path of said actuating linkage whereby said automatically moving guide is caused to swing upwardly to its slug clearing position in automatically timed relation to every actuation of said jogger, and a cushioning spring interposed between said operating lever and said slug jogger whereby the motion of said jogger can be yieldingly interrupted if the jogger should press a slug laterally against said automatically moving guide before said guide is raised to slug clearing position.

4. In slug-sawing apparatus for use in connection with a type casting machine wherein said apparatus embodies means for sawing type slugs produced by said typesetting machine, the combination therewith of an inclined platform serving as a galley for the type slugs, a delivery chute for directing the slugs from said sawing means down upon said platform, a slug jogger at one side of said delivery chute having a thrusting face operable to push the type slug laterally on said platform, an automatically moving guide at the other side of said delivery chute, pivot means for said automatically moving guide defining a pivot axis therefor disposed above said platform and extending substantially at right angles to said delivery chute, slug and thrusting face of said jogger, whereby said automatically moving guide is capable of being swung upwardly in a vertical plane remaining parallel to the adjacent side surface of the type slug so as to clear each slug as it is pushed laterally by said jogger, an operating lever arranged to transmit operating motion to said slug jogger, actuating linkage responsive to the cyclical operation of said typesetting machine for actuating said lever, an arm extending from said automatically moving guide and disposed in the path of said actuating linkage whereby said guide is caused to swing upwardly to its slug clearing position in automatically timed relation to every actuation of said jogger, and a cushioning spring interposed between said actuating linkage and said slug jogger whereby the motion of said jogger can be yieldingly interrupted if the jogger should press a slug laterally against said automatically moving guide before said guide is raised to slug clearing position.

5. In slug-sawing apparatus for use in connection with a type casting machine wherein said apparatus embodies means for sawing type slugs produced by said typesetting machine, the combination therewith of an inclined platform serving as a galley for the type slugs, a delivery chute for directing the slugs from said sawing means down upon said platform, a slug jogger at one side of said delivery chute having a thrusting face operable to push the type slug laterally on said platform, an automatically moving guide at the other side of said delivery chute, pivot means for said automatically moving guide defining a pivot axis therefor disposed above said platform and extending substantially at right angles to said delivery chute, slug and thrusting face of said jogger, whereby said automatically moving guide is capable of being swung upwardly in a vertical plane remaining parallel to the adjacent side surface of the type slug so

as to clear the slug as it is pushed laterally by said jogger, an operating lever arranged to transmit operating motion to said slug jogger, actuating linkage responsive to the cyclical operation of said typesetting machine for actuating said lever, and an arm extending from said automatically moving guide and disposed in the path of said actuating linkage whereby said guide is caused to swing upwardly to its slug clearing position in automatically timed relation to every actuation of said jogger, the upwardly swinging end portion of said automatically moving guide having its lower edge notched out to form a sloping bottom edge which lies substantially par-

allel to said platform and to the top edge of the slug in its slug clearing position.
